HEIKICHI ONISHI, OF KEIJO, CHOSSEN, JAPAN

SUPERVISORY SIGNALING SYSTEM FOR TOLL TELEPHONE SERVICE TIMING

Application filed December 11, 1928, Serial No. 325,185, and in Japan December 28, 1927.

My invention relates to improvements in supervisory signaling systems for toll telephone service timing, and particularly to the system for making indication, before a toll board operator, of the lapsing of one unit time of conversation, a rated fee being charged for such unit time.

An object of my invention is to obtain means for giving supervisory signals to a toll board operator automatically when one unit time of conversation is over. Another object of my invention is to provide means for automatically indicating the beginning and lapsing of the unit time. A further object of my invention is to obtain means for energizing a plurality of supervisory signaling apparatus from a common battery, preventing its undesirable momentary heavy discharge. A still further object of my invention is to obtain means for automatically restoring the signaling apparatus to the normal position, after the toll telephone conversation is over.

There are many other objects of my invention, which, together with the foregoing, will appear in the following description. In order that the invention may be fully understood, there will now be described, by way of example, and with reference to the accompanying drawings, wherein:—

Fig. 1 is a diagram showing one embodiment of my invention, and Fig. 2 shows three positions of the key K shown in Fig. 1. Fig. 3 is a diagram showing another embodiment of my invention, and Fig. 4 shows three positions of the key K shown in Fig. 3.

Referring to Fig. 1, the system is shown in the normal or non-operated position. The reference character K designates a manually operable rotary key, having contacts 31 and 32, and a suitable handle member N. The handle member N may be rotated through 180 degrees of angle, in order to operate the key into three positions, viz., "normal", "start", and "stop" positions, as shown in Fig. 2.

L is a supervisory signal lamp, and M is a stepping magnet which drives stepping switches A and B, as hereinafter described. The magnet is of the known type, and is connected, as will be understood, to the rotatable shafts of the stepping switches by any suit-

able mechanical connections. When the magnet is energized it drives the shaft of stepping switch to the extent of one step, and when deenergized the magnet is restored to normal without actuating the shaft and becomes ready for next stepping of the same. Any suitable means may be employed, such as a pawl connected to the magnet and a ratchet wheel secured to the shaft. A supervisory signaling switch A comprises a bank of contacts, 0 to 29 inclusive, and a wiper 33, while a stepping switch B, for restoring the switch A to its normal position, comprises a bank of contacts 0' to 29' inclusive, and a wiper 34. The wipers 33 and 34 normally engage the contacts 0 and 0' respectively, and when operated, they are simultaneously or synchronously driven by the magnet M in the direction shown by the associated arrows, step by step, sweeping over the respective banks of contacts.

Among the bank contacts of the switch A, the contacts 25 to 28 inclusive are united into a continuous strip, and connected to a source of energy V, which may be a usual common-battery as is provided for the telephone exchange service. All of the contacts of the bank B, except the contact 0', are also electrically connected together, or united into a continuous strip, which is connected to a conductor leading to the contact 31 of the key K.

A suitable interrupter 38 is connected between the last contact 29 of the bank A, and the current source V. In the drawings, the interrupter 38 is shown as comprising a rotatable member, having a plurality of alternately arranged contact segments 38' and insulating material 38'', and cooperating with a pair of contact brushes. The rotatable member is driven by suitable means, such as an electric motor 39.

D and F are relays, respectively having contacts d and f, and in combination, constitute a relay-interrupter, the operation of which will be hereinafter described. The resistance of the winding, as well as, the sensitivity, of the relay D are made much higher than those of the magnet M, so that the magnet M cannot be operated when it is energized in series circuit with the relay D.

In order to transmit driving cement impulses to the magnet M, there is provided a contactor C, a current distributer W, a distributer controlling device X, a magnet T, and a relay-interrupter comprising two relays R and S. The contactor C is actuated by a rotatable cam 40, continuously operated by a clock mechanism 41, and is so arranged that the contactor C is intermittently closed at a uniform rate, say, once for every six seconds. When the contactor C is closed, the relay R is energized on a circuit from the battery V, through the contactor C, the contact u and wiper 36 of the switch X, the winding of the magnet T and the relay R in series relation, to the common return or ground E. The resistance of the winding, as well as the sensitivity, of the relay R are made so much higher than those of the magnet T, that the magnet T cannot be operated at this time. When energized the relay R closes its contact n, whereby an energizing circuit for the relay S is completed, resulting in the closing of its contact s. The relay S has a well-known retarding metal ring 42 disposed around its core, so that its operation is suitably retarded in order to secure a proper stepping operation of the magnet T. When the contact s is closed, the winding of the relay R is shunted out of the above-traced circuit, and the magnet T is sufficiently energized to drive the wipers 35 and 36 of the switches W and X simultaneously, to the second contacts p1 and v of the respective banks W and X.

As the result of the closing of the contact s, the relay R is de-energized, to open the energizing circuit of the relay S. After a short time interval which is sufficiently long to permit the magnet T to operate properly, the contact s is open, and the energizing circuit for the relay R is completed from the battery V, through the contact v and wiper 36 of the switch X, the windings of the magnet T and relay R in series relation, to the ground.

Thereafter the relay-interrupter R and S repeat similar operations to periodically energize and de-energize the magnet T, which drives the wipers 35 and 36, step by step in synchronism, in the direction shown by the respective arrows. As illustrated, all of the contacts of the bank X, except the first one u, is made integral with the second contact v, and the wiper 36 is continuously connected to the battery V after the operation has started. The wipers 35 and 36 complete their one cycle of operation during six seconds, the time interval between every closing of the contact C. The wiper 35, therefore, engages the contact p1 at a rate of once for every six seconds, and current impulses are transmitted to the key K connected to the contact p1. The duration of such engaging is determined by the rotating speed of the wiper 35, and

may be adjusted by the adjustment of the retarding ring 42.

In a large office where a number of the set consisting of the key K and associated supervisory signaling apparatus are provided for the toll board, all the contacts 32 of equivalent keys K are respectively connected to the series of contacts p1, p2, p3, etc., of the switch W, which constitutes a current distributer and prevents simultaneous energization of all the supervisory signaling apparatus, protecting the common-battery V from any undesirable momentary heavy discharge.

It will readily be understood that the current distributer may be omitted, if a heavy discharge may be allowed, or there is only a small number of supervisory signaling apparatus, in which case the key contact 32 may be directly connected to the contactor C.

The system shown is disposed on a toll board, and is designed for supervising a three minutes' toll conversation. The rated fee is charged for every three minutes' conversation, which time is called a "unit time" in the present description.

Now assume that the toll board operator has connected together the calling and called parties or subscribers, and allowed the conversation to start. The operator then actuates the key K to the "start" position, to complete the energizing circuit of the magnet M at the contact 32. Consequently, as will readily be understood, current impulses are transmitted to the magnet M at every six seconds from the current distributer W, and by each impulse, the wipers 33 and 34 are driven one step in the direction shown by the arrows. After the 25th impulse is transmitted to the magnet M, the wiper 33 engages the continuous strip 25-28, and the supervisory signal lamp L is energized on a circuit from the battery V, through the strip 25-28, the wiper 33 and the lamp L, to the ground E, and the operator is notified thereby that there has been lapsed 25×6 seconds, that is, 2 minutes and 30 seconds after the conversation was started, and that the unit time will be over by 30 seconds thereafter. The lamp L is kept energized until the last but two, or the 28th impulse is sent to the magnet M, and by the 29th impulse, the wiper 33 is stepped to the contact 29, where the energizing circuit for the lamp L is transferred to the circuit including the interrupter 38, and the lamp L flickers in accordance with the operation of the interrupter 38. This notifies the operator that the unit time will be over at 6 seconds thereafter, and the last or the 30th impulse actuates the magnet M to drive the wiper 33 to the normal position, whereupon the signal lamp L is extinguished to indicate that one unit time of three minutes is over.

If the conversation is allowed to be continued for the second three minutes, the key K is kept in the "start" position, and another

cycle of supervisory operation will be effected just in the same manner as above stated, and when the toll telephone is rung off, the operator actuates the key K to the "normal" position.

When the toll telephone is rung off before the three minutes duration is over, say, at such a time that the wiper 33 engages the contact 25, the operator may actuate the key K to the "normal" position, in order to have the apparatus restored to the normal position rapidly. At the "normal" position of the key K, with the wipers 33 and 34 at their intermediate positions, a driving circuit for the magnet M is prepared from the battery V, through the relay-interrupter D, F, the wiper 34 and contact strip 1'-29' of the switch B, the contact 31 of the key K and the magnet M, to the ground. The magnet M then receives driving impulses by periodic energization and de-energization of the relays D and F, and consequent periodic opening and closing of the relay contacts d and f, the operation being similar to that of the relay-interrupter R, S, as hereinbefore described. The wipers 33 and 34 are, therefore, driven step by step to be restored to the normal positions illustrated.

During the unit time of conversation, there may happen in the toll telephone system some faults which interfere with the conversation, and the toll telephone connection will be open during the persistence of such faults. It is an usual practice that such a time interval of fault condition is deducted from the total time of conversation to be charged.

In order to make such deduction of the non-charged time interval from the total duration of the toll connection, the operator is to actuate the key K to the "stop" position. In this position, both of the contacts 31 and 32 are open and the switches A and B are kept standstill at intermediate contacts, say, the 24th contact of the bank A and the corresponding position on the strip 1'-29' of the bank B, respectively. When the fault is over, the operator actuates the key K to the "start" position, and the wipers 33 and 34 are operated in the manner described, for the remaining period of the unit time.

If the unit time is other than three minutes, it will be readily understood that the system may be changed to meet with this condition by changing the number of contacts of the banks A and B, or the period between the successive current impulses transmitted from the contactor C. It will also be understood that a group of several supervisory devices may be connected to one contact p1, p2, p3, etc., of the current distributor W, directly or by intermedium of suitable relay devices.

In Fig. 3, a modified system is shown, wherein the supervisory signal lamp is once lighted at the beginning of the unit time, in order to notify the operator that the super-

visory operation has started in a proper manner, and in which like reference characters are employed to designate similar parts shown in Fig. 1, except certain differences hereinafter pointed out. In this modification, the key K is provided with an additional contact 37 connected between the interrupter 38 and the contact 0 of the bank A, while the first contact 1 thereof is connected to the second contact p2 of the current distributor W, and the contact 26-29 of the bank A are united together and connected to the common-battery V.

With the above arrangement, when the key K is operated to the "start" position, in addition to the closure of the contact 32, the contact 37 is also closed, and a circuit is completed for the supervisory signal lamp L, from the battery through the interrupter 38, the contact 37, the contact 0 and wiper 33 of the switch A, and the lamp L, to the ground, and the lamp L flickers accordingly, thus showing that the supervisory operation is started.

Upon the first driving operation of the magnet M, the wiper 33 is stepped to the bank contact 1, and the lamp L is extinguished. At this time, the wiper 35 of the current distributor W will have passed the bank contact p1 to which the magnet M is now connected, and will sweep over the remaining bank contacts during the remaining time of the six seconds' period.

At the time when the operator actuates the key K to the "start" position, if the wiper 35 is on the bank contact p0 or p1, there occurs the above-mentioned operation, but if the wiper 35 has just passed the contact p1, but is coming to engage the next contact p2, the lamp circuit is instantaneously completed from the battery V, through the wiper 35, the contact p2, the bank contact 1 and wiper 33 of the switch A, and the lamp L, to the ground. The lamp L is then lighted to show the fact that the supervisory operation is properly started, but this lamp is extinguished as soon as the wiper 35 has passed the contact p2. Upon the 26th operation of the magnet M, the wiper 33 engages the bank contact 26, and the lamp L is therefore energized over a circuit from the battery V, through the bank strip 26-29 and wiper 33 of the switch A, and the lamp L, to the ground. This energizing circuit is kept complete until the last or 30th operation of the magnet M is effected, thereupon the lamp circuit being transferred to the flickering circuit hereinbefore-traced, to notify the operator that the unit time is over, as the wiper 33 now engages the original contact 0.

It will be noted that there might have occurred a certain time error for the first unit time of three minutes, if the first impulse should not be sent to the magnet M at a time just after six seconds from the time when

the key K is operated to the "start" position. This error will be six seconds at the maximum which will occur if the first impulse is sent immediately after the key K is operated.

5 In order to minimize such errors, the period of operation of the contactor C may be made shorter, say, 3 seconds, and the number of steps or bank contacts of the switches A and B doubled, and the maximum error will be reduced to three seconds.

10 It will be readily understood that the sequence of energization and de-energization of the supervisory signal lamp L for obtaining the required supervisory indications may be modified in various ways, by changing the connections of the bank contacts of the switch A among themselves and also with the source of electric current. It will also be obvious that the lamp L may be substituted by some 15 other suitable signal devices, and it is to be understood that such changes in the construction, form, arrangement and connection of the component parts of my invention may be made as shall fall within the scope of the ap- 20 pended claims.

25 I claim as my invention:—

1. In a supervisory signaling system for toll telephone service timing, comprising an electrical signal device having energizing circuit, a stepping switch having a wiper and a bank of contacts, restoring means therefor having a wiper and a bank of contacts, and a magnet having an energizing circuit for driving said wipers step by step, contactor means 30 adapted to be opened and closed at predetermined time intervals, a source of electric current connected thereto, and key means for controlling said energizing circuit for said magnet, the bank of contacts of said stepping 35 switch being so arranged as to open and close with predetermined time intervals the energizing circuit of said electrical signal device in accordance with the operation of the wiper of said stepping switch.

40 2. In a supervisory signaling system for toll telephone service timing comprising an electrical signal device having an energizing circuit, a stepping switch comprising a wiper and a bank of contacts for controlling the en- 45 ergizing circuit of said electrical signal device, another set of a wiper and a bank of contacts, and a magnet having a normal energizing circuit for driving said wipers step by step, a relay interrupter, key means for mak- 50 ing driving connections between said rotary magnet and said relay interrupter through said second set of wiper and bank of contacts, contactor means adapted to be opened and closed at predetermined time intervals, a 55 source of electric current for said magnet and relay interrupter, said key means controlling said normal energizing circuit of said stepping magnet.

60 3. In supervisory signaling system for toll telephone service timing, comprising an elec-

trical signal device having energizing circuit therefor, a stepping switch having a wiper and a bank of contacts, means operable for restoring said stepping switches to normal, and having a wiper and a bank of contacts, 70 and a stepping magnet, having an energizing circuit therefor, for driving said wipers step by step, contactor means adapted to be opened and closed at predetermined time intervals, a source of electric current controlled thereby 75 for said stepping magnet, key means for controlling said energizing circuit for said stepping magnet, the bank contacts of said stepping switch being so arranged as to open and close said energizing circuit of the electrical 80 signal device with predetermined intervals, and said contactor means including a current distributing device for connecting said energizing circuit for said stepping magnet to said source at predetermined time intervals 85 once for one cycle of operation of said contactor means.

In witness whereof I affix my signature.
HEIKICHI ONISHI.
